UNITED STATES PATENT OFFICE.

MILTON D. STOCKING, OF LINDENWOOD, ILLINOIS.

FEED-TROUGH.

1,126,907.

Specification of Letters Patent.

Patented Feb. 2, 1915.

Application filed September 15, 1913. Serial No. 789,853.

To all whom it may concern:

Be it known that I, MILTON D. STOCKING, a citizen of the United States, residing at Lindenwood, in the county of Ogle and the 5 State of Illinois, have invented certain new and useful Improvements in Feed-Troughs, of which the following is a specification.

This invention relates to feed troughs for stock, and has for its object the construction 10 of an improved trough which shall be easily manufactured, require but small space when being shipped in large numbers, and meet the different requirements subject to such an article during use.

15 The further object of my invention is to provide a novel means for supporting and for holding the trough in position, the means for holding the trough in connection with the supporting means being detachable 20 from said supporting means.

A further object is the provision of an improved construction of trough corner.

In the accompanying drawings: Figure 1 is a plan view of my improved feed trough. 25 Fig. 2 is a vertical transverse section through the trough as taken on the line of section 2—2 of Fig. 1. Fig. 3 is a view in perspective of one of the detachable trough clamps. Fig. 4 is a detail view in perspective of a trough corner, partially fragmentary, illustrating the construction of said corner.

The trough supporting means may be suitably secured to a flooring or base, 35 which has here shown spaced base-bars 5 to which the supporting means are attached. The trough supporting means are in the form of metal strips bent in loop form to form a base portion, a trough receiving portion and side portions with which fastening devices are adapted to coöperate to retain a trough in position in said trough receiving portion. These strips 6 span the base bars transversely, are bent in irregular 40 loop form with each end portion being joined in a base 7, the base being bolted to the base-bars at 8, the center and upper portion of the strip being depressed forming a downwardly converging trough receiving 45 portion 9, the bottom of said trough receiving portion being riveted at 10 to the base 7, and the sides 11 of the looped strip serve as struts or braces for said trough receiving portion and also by their openings 12 as 50 part of a fastening means by which a trough 55 is locked in position in said trough receiv-

ing portion. These looped supports may be spaced suitably upon a base, in a necessary number, according to the length of the trough.

The trough is formed of sheet metal, has a bottom 13, bent up sides 14 which conform to the taper of the trough receiving portion 9, and said bottom and sides have segment end-flaps 15 to which are riveted trough ends 16. The trough sides 14 have tops 17 which are turned downwardly at their outer sides and then back upon themselves forming depending rims 18, and likewise have the ends 16. The ends of tops 17 are lapped one over the other at the corners of the trough, the top-end 19 of a trough end 16 overlapping the top-end 20 of a trough side 14, and the overlapped portions are riveted at 21. Since the rims 18 do not overlap at the ends, L-shaped corners 22 are located with one wing intermediate the turned under portions of each rim, they being secured in this position during the forming and turning under of the rim 18.

Clamping members of U-shape construction have the head 23 of the U-construction adapted to span the trough tops 17, and have arms 24 depending serving as spring arms, these arms having hooked ends 25 which locate in openings 12 in the brace portions 11. The hooked ends 25 of the clamping member are of a distance apart less than the distance between two opposite openings 12, and these arms 24 may be forced yieldingly apart, so 90 that their ends 25 may engage in openings 12, thereby holding the trough fixed with the support. To remove the clamping member any suitable rigid article or tool may be inserted intermediate an arm 24 and side 95 11 to spring the hooked end of arm 24 from its catch.

Feed troughs and especially those of metal construction must have transverse braces across their tops to retain them in 100 position and from bulging, and where these braces are fixed to the tops and the troughs in shipping are piled one upon another they occupy a maximum trough space; and in my improved construction of trough it will 105 be noticed that because of the supporting means and associated clamping means, that the troughs with their tapered sides and ends may be placed one within the other, telescoping, and thus occupy but a small 110 space when being shipped. With a trough in use, when it is desirous to remove the

trough for any purpose, the clamping members may be easily removed as above explained and the trough may be lifted from its support, this being desirable for cleaning the trough, repairing same, and for removing ice formed therein, by inverting the trough, the ice coming out readily because of the tapered sides and ends of the trough.

It will be noticed that the looped supporting members, simple in construction, serve several functions, that of a base, a trough receiving support, and part of a means for locking the trough fixed in the receiving portion of the support.

15 1. I claim as my invention:

1. In an article of the character set forth, a trough, a support therefor, a clamping member having yieldable ends, and said member having a portion overlying the trough and having its ends detachably spring engageable with said support whereby the trough is held clamped to the support and said ends are free to be yieldingly detached to permit the clamping member to be removed and the trough to be removed from the support.

2. The combination with a trough, of a support therefor formed of a metal strip having sides associated with sides of the trough and having an outer side spaced from each of said trough associated sides, each outer side having an opening therein, and a clamping member overlying said trough and having yieldable ends spring engageable in said openings in the outer sides.

3. In an article of the character set forth, a trough of sheet metal construction having corner-tops overlapped and having the outer sides of the tops turned downwardly to form a rim, and L-members located at the inner sides of the rims and associated therewith, the lower portions of said rims being turned inwardly and upwardly so as to en-

gage and hold said L-members in fixed position.

4. The combination of a trough formed with downwardly converging sides and a horizontally disposed rim at the upper end of said sides, a pair of supports for said trough, each formed of a single strip of metal the center portion of which is shaped to receive said converging sides of the trough, and the end portions of which form sides spaced from said trough-receiving portions, each side having an opening therein, and inverted U-shaped members overlying the trough one above each support with its depending ends shaped to fittingly engage said openings.

5. The combination of a support, a trough removably mounted thereon, the support having apertures at opposite sides of the trough opening at the outer side thereof, and an inverted U-shaped clamping member overlying the trough and having its ends shaped to be spring engageable in said apertures.

6. The combination of a support, a trough removably mounted thereon, an inverted U-shaped member overlying the trough, having yieldable side members the ends of which are turned inwardly, and the outer sides of the support having transverse face portions to receive in locked engagement said inturned ends of the U-shaped member, when said member is moved downwardly against yielding resistance of its sides.

In testimony whereof I have hereunto set my hand in presence of two subscribing witnesses.

MILTON D. STOCKING.
